UNITED STATES PATENT OFFICE.

ANTHONY TRIPPI, OF BUFFALO, NEW YORK.

DESIGN FOR A MIRROR.

Application filed April 23, 1925. Serial No. 13,193. Term of patent 7 years.

To all whom it may concern:

Be it known that I, ANTHONY TRIPPI, a citizen of the United States, residing at Buffalo, in the county of Erie and State of New York, have invented a new, original, and ornamental Design for Mirrors, of which the following is a specification, reference being had to the accompanying drawing forming part thereof.

The figure is an elevation of a mirror showing my new design.

I claim:

The ornamental design for a mirror, as shown.

ANTHONY TRIPPI.
